COMBINATION PENCIL BOX, RULER, AND PENCIL SHARPENER

George L. Price, Great Neck, N. Y.

Application April 9, 1949, Serial No. 1,878

Term of patent 14 years

(Cl. D74—21)

To all whom it may concern:

Be it known that I, George L. Price, a citizen of the United States, residing at Great Neck, in the county of Nassau and State of New York, have invented a new, original, and ornamental Design for a Combination Pencil Box, Ruler, and Pencil Sharpener, of which the following is a specification, reference being had to the accompanying drawings, forming a part thereof.

In the drawings:

Fig. 1 is a top plan view of a combination pencil box, ruler and pencil sharpener showing my new design with broken away portions for convenience of illustration;

Fig. 2 is a side elevational view thereof with a portion of the box broken away for convenience of illustration;

Fig. 3 is an end elevational view thereof; and

Fig. 4 is a cross-sectional view taken on line 4—4 of Fig. 2.

I claim:

The ornamental design for a combination pencil box, ruler, and pencil sharpener, as shown and described.

GEORGE L. PRICE.
